UNITED STATES PATENT OFFICE

KARL WINTTERLIN, OF COLOGNE, GERMANY, ASSIGNOR TO MOTORENFABRIK DEUTZ,
AKTIENGESELLSCHAFT, OF COLOGNE-DEUTZ, PRUSSIA, GERMANY

GEARING DEVICE FOR INTERNAL COMBUSTION MULTICYLINDER OIL ENGINES

Application filed July 8, 1927, Serial No. 204,329, and in Germany June 23, 1927.

This invention relates to the starting arrangements of internal combustion oil engines.

In multicylinder internal combustion oiling engines provided with compressed air starting apparatus, it has already been proposed to start all the cylinders simultaneously or to shift, in respect to a portion of the cylinders, from the operation of said cylinders by the starting apparatus to their operation by the apparatus for the fuel operation of the engine. Such a starting operation offers no difficulty if the lever or other controlling member which effects the starting of the engine be provided separately from the regulating and fuel feeding device of the fuel pump, which works simultaneously for all the cylinders. If the operation of starting and that of regulating the feed of the fuel pump is to be carried out by a single organ, then for every cylinder group one of these double acting organs for starting and working would be necessary. Such an arrangement would require not only that both hands of the operator be used simultaneously, since there would be at least two groups of cylinders, but furthermore his attention would have to be particularly directed to seeing that always the same amount of fuel be fed to each of the cylinder groups, in order to avoid irregular stresses on, or overloading of, the different groups of cylinders. According to the present invention the undesirable exertion and fatigue thus imposed upon the operator is avoided by placing the control organs or members for actuating the engine so close together that they may be joined or coupled directly and immediately by a simple pin or bolt coupling or other suitable coupling means. In accordance with this invention it is desirable so to construct this coupling means that the coupling bolt or pin that is slidably mounted in the handle of one of said levers, can be slid into a bore in the handle of the other lever without becoming disengaged from the first lever. The thus coupled two levers, however, are each provided with a locking pawl adapted to engage a toothed segment and thus hold each lever against movement until said locking pawl

is manually disengaged from its segment. Where the two levers are thus coupled, therefore, it would be necessary, before the coupled levers could be moved, first to disengage the two locking pawls from their respective segments, which is a very inconvenient and cumbersome operation. In order to avoid this disadvantage, the arrangement may be such, that when the controlling members or levers are coupled, the coupling means, such as the bolt in this instance, on the one controlling member or lever, renders the locking means, in this instance the pawl, of the other controlling member or lever, inoperative, so that the locking in position of the two controlling members or levers can be effected by only one locking means or pawl.

In the drawings one illustrative embodiment of the invention is shown diagrammatically.

Fig. 1 shows the arrangement of the working devices of an internal combustion oil engine according to the invention;

Fig. 2 shows a longitudinal section, when the coupling means or bolt is disengaged;

Fig. 2^a shows a side view of the locking means of one control member or lever;

Fig. 2^b shows a side view of the locking means of the other controlling member.

Fig. 3 shows a longitudinal section when the coupling means is engaged;

Figs. 3^a and 3^b show corresponding views when the coupling means is engaged;

Fig. 4 is a front elevation of a machine embodying the present invention, showing the two gearings in their relation to the two cylinder groups.

The levers controlling the two gears for the two groups of cylinders are designated by a¹, a² respectively.

In Fig. 1 the lever a¹ is shown in an operative position which corresponds to a position in which half the full fuel supply is delivered to the engine. Line o—III corresponds to the full supply of fuel, and line o—I corresponds to the position in which no fuel is supplied to the engine, while line o—II corresponds to the starting position, in which the pawl b¹ of lever a¹ engages the teeth of segment c¹, the roll f of the starting roll car-

rier g naturally has moved out of operative position relative to the starting cam h , by operation of the levers a' , e , and thus the starting valve i remains closed. In the meantime 5 the governing cam disc k , which is connected to lever a^1 , acting through roll l and levers or connecting rods m , has fed to the fuel pump o a certain amount of fuel. In order to actuate the two levers from I to III, namely 10 from stop to full load, with one hand and always to feed the same and equal amount to the fuel pump, a pin or bolt q is provided in the handle p^2 of lever a^2 . This bolt q carries on its end a button or head r , which 15 can be pressed against the action of a spring s , into a corresponding recess t in the handle p' (Fig. 3). It is retained in this position by a pawl u , which can be for that purpose brought into engagement with a groove q^1 20 in the bolt q . In order to bring the bolt q into position to engage the recess t , as shown in Fig. 3, the pawl b^1 must be brought out of the position according to Fig. 2^b into the position 25 according to Fig. 3^b. Only in the position according to Fig. 3^b can the bore b^1 of the pawl b^1 be brought into alinement with the recess t . In the position according to Fig. 3 the pawl b^1 is disengaged from its segment 30 c^1 by engagement of bolt q in its bore b^1 , whereby it is held out of engagement with its toothed segment, and the operator, holding grip p^2 of lever a^2 and releasing the pawl b^2 of said lever, can bring the coupled controlling members or levers a^1 and a^2 into any de- 35 sired position. If the internal combustion oil engine is to be started, lever a^1 is uncoupled from lever a^2 by pressing on pawl u , and bolt q then snaps out of the recess t by action of spring s . 40 By turning levers a^1 , a^2 into the position 0-II, the engine will be started. As soon as the first rotations have taken place, preferably one of the two levers, for instance lever a^2 , is brought into one of the working positions 45 between I and III, past the stopping position 0-I. As soon as the first ignitions of the cylinder group corresponding to lever a^2 take place, lever a^1 is brought from starting position over into the working position already 50 occupied by a^2 . Then, by bringing the bore b^1 of pawl b^1 into alinement with the recess t and pressing on head or button r , the bolt q can be caused to engage said bore b^1 , and recess t , so that the two controlling members 55 or levers a^1 and a^2 are coupled, and the pawl b^1 being thus held out of engagement with its toothed segment, the two levers a^1 , a^2 can be brought into any desired position by manipulating the pawl b^2 . 60 The starting rods are indicated by z in Fig. 4.

I am aware that the invention may be embodied in other specific forms without departing from the spirit or essential attributes 65 thereof and I therefore desire the present

embodiment to be considered in all respects as illustrative and not restrictive, reference being had to the appended claims rather than to the foregoing description to indicate the scope of the invention. 70

What I claim as my invention and desire to secure by United States Letters Patent is:

1. In a multicylinder liquid fuel internal combustion engine having its cylinders arranged in groups of one or more cylinders, in combination, air starting operating mechanism; fuel supply controlling mechanism; a controlling member to operate said air starting operating and fuel supply controlling mechanism in respect to one group of cylinders; a controlling member to operate said air starting operating and fuel supply controlling mechanism in respect to another group of cylinders; coupling means whereby said controlling members may be coupled to be operable in unison by movement of one of said controlling members to operate said air starting operating and fuel supply controlling mechanism in respect to both groups of cylinders; separate locking means for said controlling members; and means to render one of said locking means inoperative when said levers are coupled. 80

2. In a multicylinder liquid fuel internal combustion engine having its cylinders arranged in groups of one or more cylinders, in combination, air starting operating mechanism; fuel supply controlling mechanism; a controlling member to operate said air starting operating and fuel supply controlling mechanism in respect to one group of cylinders; a controlling member to operate said air starting operating and fuel supply controlling mechanism in respect to another group of cylinders; locking means for said controlling members; and coupling means 90

operable to couple said controlling members together, to render them operable in unison by movement of one of said controlling members to operate said air starting operating and fuel supply controlling mechanism in respect to both groups of cylinders, said coupling means rendering the locking means 100

of one of said controlling members inoperative when said coupling means is in operative 110

position.

3. In a multicylinder liquid fuel internal combustion engine, in combination, air starting operating mechanism; fuel supply controlling mechanism; a controlling member to operate said air starting operating and fuel supply controlling mechanism in respect to one group of cylinders; a controlling member to operate said air starting operating and fuel supply controlling mechanism in respect to another group of cylinders; separate locking 120

means for each of said controlling members; a locking member mounted on one of said controlling members and movable to engage the other controlling member and lock 130

said controlling members together when the locking means of one of said controlling members is in inoperative position, and to maintain said locking means in inoperative position while said controlling members are locked together.

4. In a multicylinder liquid fuel internal combustion engine, in combination, starting mechanism for said engine; apparatus for the fuel operation of said engine; controlling means, for the operation of said starting mechanism and said apparatus, comprising two independently manually operable controlling members, the one to operate said starting mechanism and said apparatus for the fuel operation of said engine; in respect to one or more cylinders of said engine, and the other to operate said starting mechanism and said apparatus for the fuel operation of said engine in respect to one or more other cylinders of said engine; separate locking means, movable from operative to inoperative position, for each of said controlling members; and a locking member mounted on one of said controlling members and movable to engage the other controlling member and lock said controlling members together when the locking means of one of said controlling members is in inoperative position, and to maintain said locking means in inoperative position while said controlling members are locked together.

5. In a multicylinder liquid fuel internal combustion engine, in combination, starting mechanism for said engine; apparatus for the fuel operation of said engine; controlling means for the operation of said starting mechanism and said apparatus, comprising two independently movable manually operable controlling members, the one to operate said starting mechanism and said apparatus for the fuel operation of said engine; in respect to one or more cylinders of said engine, and the other to operate said starting mechanism and said apparatus for the fuel operation of said engine in respect to one or more other cylinders of said engine; a pair of toothed segments; a locking pawl carried by each of said controlling members and each movable into and out of locking engagement with one of said toothed segments; a coupling bolt carried by one of said controlling members and movable to engage the other controlling member and lock said controlling members together when the locking pawl of one of said controlling members is out of engagement with its toothed segment, and to maintain said locking pawl out of engagement with said toothed segment while said controlling members are locked together.

KARL WINTTERLIN.
